INVENTOR:

UNITED STATES PATENT OFFICE.

RICHARD DEAN, OF FALL RIVER, MASSACHUSETTS.

DESIGN FOR A FRYING-PAN.

SPECIFICATION forming part of **Design No. 27,436, dated July 27, 1897.**

Application filed May 11, 1897. Serial No. 636,104. Term of patent 7 years.

To all whom it may concern:

Be it known that I, RICHARD DEAN, a citizen of the United States, residing at Fall River, in the county of Bristol, in the State 5 of Massachusetts, have invented and produced a new and original Design for Frying-Pans, of which the following is a specification, reference being had to the accompanying drawing, which is a plan view of said de-
sign.

My said design relates to pans for frying eggs, and the leading feature of the design is a group of depressions in the bottom of the frying-pan having the form and outline of 15 fowls.

In the drawing I show in plan view a frying-pan having the usual flaring sides and a handle projecting therefrom, made near its

junction with the pan, in the form of a bird with outstretched wings. The bottom of the 20 pan has certain depressions, the form and relative positions of which are fully shown in the drawing, each depression being in the form of a fowl—a duck or a hen. Channels or grooves extend from one of said depressions to the others. The depressions so formed are grouped triangularly and occupy the greater part of the bottom of the pan. They each have beveled or sloped sides.

What I claim is—

The design for a frying-pan herein shown and described.

RICHARD DEAN.
